UNITED STATES PATENT OFFICE.

ALONZO E. RHOADES, OF HOPEDALE, MASSACHUSETTS, ASSIGNOR, BY MESNE ASSIGNMENTS, TO DRAPER CORPORATION, OF HOPEDALE, MASSACHUSETTS, A CORPORATION OF MAINE.

FILLING-END REMOVER FOR LOOMS.

1,212,681.

Specification of Letters Patent. Patented Jan. 16, 1917.

Application filed October 29, 1914. Serial No. 869,206.

To all whom it may concern:

Be it known that I, ALONZO E. RHOADES, a citizen of the United States, and residing in Hopedale, county of Worcester, and State of Massachusetts, have invented an Improvement in Filling-End Removers for Looms, of which the following description, in connection with the accompanying drawings, is a specification, like characters on the drawings representing like parts.

The invention to be hereinafter described relates to filling replenishing looms, and more particularly to means for removing from the loom the end of the filling that projects from the cloth selvage after a replenishing operation, that it may not be carried into the shed. As a result of the replenishing operation in looms of the filling replenishing type, an end of filling is left projecting from the cloth selvage, which is liable to find its way into the shed during weaving, with the result that defects in the cloth occur. Attempts have heretofore been made with more or less success, to prevent the occurrence of such defects in the cloth by providing means to engage and hold the filling end, sever it at the cloth selvage, and then drop the free piece of filling or withdraw it from the zone of operation of the loom parts. Such devices have caused the introduction of more or less complicated and delicate mechanism into the loom structure which is particularly noticeable in eliminating the spent filling end from what are technically known in the art as "feeler looms."

With these general facts in view, the present invention aims to simplify and produce more efficient and reliable means for removing the filling end from looms following a replenishing operation; and, while it is herein shown and described as associated with a loom of the "feeler" type, it is to be understood that the invention may be used in connection with other types of looms and that in its true scope, the invention is not restricted to the details or particulars as illustrated and described, but may be varied within the definition of the invention as pointed out by the claims.

In the drawings: Figure 1 shows in plan view sufficient parts of one end of a loom provided with a good practical form of the invention to make clear its construction and operation; Fig. 2 is a cross-section substantially on the line 2--2 of Fig. 1, showing

one form of means that may be conveniently employed to part the filling adjacent the shuttle containing the filling carrier about to be abandoned, the said means being shown in its normal or inoperative position; Fig. 3 is a front end view at the lower portion of a loom equipped with a suction pump which may be associated with other features of the invention; Fig. 4 is a section on the line 4--4, Fig. 1; and Fig. 5 is a detail showing a screen for intercepting the filling ends in the filling end receiver.

In prior attempts to remove the filling end from a filling replenishing loom of the type wherein replenishment is effected prior to complete exhaustion of the filling in the shuttle, a thread parting mechanism has served to part the filling adjacent the shuttle and another parting mechanism, such as a temple thread parter, has parted the filling end adjacent the cloth selvage. In some cases the severed filling end has been held by the first-named thread parting mechanism to position the filling for the action of the temple thread parter and until the call for another operation of the replenishing mechanism, and then would release the filling end as the parting mechanism was again made operative. The present invention, when associated in a loom of the above type, contemplates that the filling leading from the substantially exhausted shuttle shall be parted and then released, and that the filling end shall pass at once into the control of a part of the present invention, so that when freed from the cloth selvage, it may be removed from the loom. As a practical means to this end, the invention aims to provide a device preferably disposed between the cloth selvage and the shuttle box on the same side of the loom, which shall act pneumatically upon the filling end, preferably by suction, so that as soon as the filling of the practically exhausted shuttle has been parted near or adjacent to the shuttle, the free end thereof will pass at once into the control of the said device which will hold the filling end in position for the action of the temple thread cutter and as soon as such thread cutter has acted, will carry the now free piece of filling away from all danger of being passed into the shed.

Any character of parting mechanism may be employed to part the filling near or ad-

5 jacent to the practically-exhausted shuttle, and similarly any desired character of thread parter may be employed to sever or part the filling near the selvage of the cloth, the only essential in this respect being that the filling be parted at or substantially at the points noted, in order that it may pass into complete control of the pneumatic device referred to.

10 In the present illustrated form of parting mechanism for parting the filling adjacent the practically-exhausted shuttle, that illustrated and described in the Rhoades Patent, No. 922,511, dated May 25, 1909, is employed, but it is to be understood, of course, that this is merely typical of a means for parting the filling near to or adjacent the practically exhausted shuttle; and the temple thread cutter is herein typified as 15 of the same general character as that in the Rhoades patent, although any character of thread parter that will serve to part the filling adjacent the cloth selvage may be suitable.

20 25 The lay 1 having the usual character of shuttle box 2 at the replenishing side of the loom; the breast beam 3; the transverse rock shaft 4 for controlling the transferring mechanism not herein illustrated; the fixed blade 5; the movable blade 6 pivoted at 7 on the arm 8 and having the heel 9; the pivotal support 10; the yoke 11 having the bearings 12 and 13 and the pin 14; the jaws 15 and 16 and associated spring 17; may all 30 35 be appropriately formed, arranged, and constructed, as in the Rhoades patent, hereinbefore mentioned; and since such devices and their co-operative relations are clearly set forth and described in the Rhoades 40 patent, further elucidation herein is unnecessary.

When the filling end leading from the practically exhausted shuttle has been severed, and the severed end clamped by the 45 fixed and movable jaws of the thread parter, it is desirable that this severed end portion of the filling be freed from the clamping action of the jaws, and to this end the heel 9 of the movable jaw is provided with an 50 abutment 18 preferably formed as a roller, as indicated in Fig. 2, which is adapted to contact with a stop 19 secured in appropriate position upon the breast beam 3, as by the bolt 20, the construction being such that 55 after the thread parter has been moved rearwardly and severed the filling adjacent the practically exhausted shuttle, and the jaws have been closed and hold the filling end as set forth in the Rhoades patent, 60 on the return or forward movement of the arm 8 the abutment or roller 18 will strike the stop 19 and thereby open the jaws to free the end of the filling for a purpose that will presently appear. In order that this 65 opening or releasing movement of the part-

ing mechanism may be appropriately timed, the stop 19 has its shank portion 21 provided with a slot 22, Fig. 1, through which the bolt 20 passes, the construction being such that upon loosening the bolt 20, the stop 19 may be adjusted to cause releasing movement of the jaws 5 and 6 at the desired time.

The temple, which as a whole is designated 23, Fig. 1, is herein shown as provided with a suitable thread parter 24 adjacent the cloth selvage, but as such temple thread parter is well known to those skilled in the art and may for the purposes of the present invention be of any desired type, the particulars of its structure are not herein elucidated.

75 Secured in appropriate position, preferably upon the breast beam, is a bracket 25, Figs. 1 and 4, provided with a sleeve or tubular bearing 26, through which projects the tube or conduit 27, said tube or conduit 27 being normally held in position with its end 28 projecting toward the lay 1 by suitable means such as a spring 29, preferably 80 within the tubular bearing 26, one end of said spring bearing upon a collar 30 secured to the tube or conduit 27 and the other end finding a seat against the end abutment 31 of said tubular bearing, substantially as 85 indicated in Fig. 4,—the construction being such that should the shuttle be trapped in front of the tube or conduit 27 or fail to enter the box, the end of the tube or conduit 27 may engage the shuttle as the lay beats 90 up; and be moved forwardly thereby, without injury to the parts, as will more 95 fully appear.

100 The present invention contemplates that means be provided to maintain a current of 105 air passing inwardly of the tube or conduit 27, so that when the end of the filling a, Fig. 1, has been parted adjacent the practically exhausted shuttle, the free end of such filling may be drawn by the air suction into the tube or conduit 27, as indicated by the dotted lines in Fig. 1; and that thereafter, when the filling end has been parted at the selvage of the cloth, such piece of filling may be at once removed from all danger 110 of being carried into the shed. Various expedients will suggest themselves to those skilled in the art, for producing the air currents passing inwardly of the tube or conduit 27, and it may be that where a series of 115 looms are employed, the tubes or conduits 27 of said series of looms may be connected to a single exhausting means, such as a pump. In the illustrated form of the invention, however, the individual loom is indicated as being provided with an air pump, but it is to be understood that this is typical 120 merely of a means for producing inward air currents through the tube or conduit 27, and that individual looms may each be pro- 125 130

vided with such or equivalent air pump, or a series of looms be connected to a single pump.

Referring to Fig. 3 as illustrating an appropriate form of air exhaustion means: the cross beam 32 of the loom has rising therefrom a bracket 33 to which is appropriately secured a supporting member 34, by suitable means such as the bolt 35, said supporting member 34 serving to sustain a cylinder 36. As a preferred means for sustaining the cylinder 36, the part 34 may be made as a part to surround the cylinder as indicated in Fig. 3, and be appropriately clamped thereupon by means of a bolt or other securing means 37.

Rising from the bracket 33 and preferably secured thereto by the bolts 38, is an arm 39 having secured thereto a bearing 40 for a shaft and band-wheel 41 carrying a crankpin 42 connected to an arm 43. The arm 43 at its upper position is provided with an appropriate connection such as a swivel pin 44 to a piston rod 45 which may reciprocate in a suitable bearing in the upper portion 46 of the arm 39, the construction being such that as the pulley 41 is rotated the piston rod 45 will be appropriately reciprocated as will be readily understood. As one means 30 for imparting such movement to the pulley 41, the shaft 47, which may be either the crank or cam shaft of the loom, is provided with a large band wheel or pulley 48 operatively connected to the pulley 41 by an appropriate belting or band 49.

The piston rod 45 passes through a suitable packing 50 at the top of the cylinder 36, and at its lower portion carries an appropriate piston 51, Fig. 3. Connected to or formed upon one side of the cylinder 36 is a chamber 52 having a pipe connection 53 with the flexible tube 54. At the lower portion of the cylinder 36 and communicating with the chamber 52, is an inlet valve 55, and preferably opposite thereto is an outlet valve 56, said valves being of usual type, and being duplicated at the top of the cylinder, although not therein shown by reason of being covered by the overlying parts, the 50 construction being such that upon reciprocation of the piston 51, air is drawn through the inlet valves 55 from the chamber 52, thereby creating a suction or partial vacuum in the flexible tube 54 and inducing currents 55 therein in the direction indicated in Fig. 3; and the air thus drawn into the cylinder is forced through the outlet valves 56, as will be readily understood. The air chamber may be variously formed, but the particular 60 construction herein described has been found a good, practical form thereof, and as hereinbefore described, each loom may be thus provided with an air pump operated in appropriate manner to produce inward currents of air through the flexible tube 54,

or a single pump located in any portion of the building may be associated with a plurality of looms and be appropriately driven from any source of power. Indeed, the construction indicated in Fig. 3 may be regarded as typical of such single pump adapted for connection with a series of looms.

The tube or conduit 27 has at its inner portion a filling end receiver herein shown 70 as a box-like device 57, Fig. 4, provided with a removable cover 58 and a screen or wire gauze 59 which will permit the passage of air but prevent the passage of pieces of filling, or other material.

Connected to the filling end receiver 57 is the flexible tube 54, the said connection being preferably formed by means of a tubular projection 60 at the bottom of the filling end receiver 57, as indicated in Fig. 4, though 80 obviously other appropriate forms of connection might be employed.

From the construction thus far described, it will be apparent that when the filling in a running shuttle has become practically exhausted, and a change of filling is indicated, the filling leading from the practically exhausted shuttle will be parted adjacent thereto, and the free end thereof will immediately be drawn into the tube or conduit 27 by the inrushing currents of air, as indicated in dotted lines, Fig. 1. The filling end will thus be maintained under light drawing tension by the currents of air passing through the tube or conduit 27 which will serve to maintain the filling in position for the action by the temple thread cutter, and when the temple thread cutter has parted the filling at the selvage of the cloth, the now free piece of filling will be drawn by the currents of air through the tube or conduit 27 and into the filling end receiver 57, where it will be intercepted by the screen or gauze 59. Obviously, the filling ends may be readily removed from the filling end receiver at any time by merely lifting the cover 58 and taking them out by hand, or otherwise. It may at times be desirable to raise the screen 59 in the filling end receiver in order to clean the same; and to this end the screen 59, which may preferably be formed of wire gauze or wire cloth, is appropriately secured to the two arms 61, which may project through the bottom of the filling end receiver as indicated in Fig. 4. As an appropriate means for supporting the screen in position in the filling end receiver, the arms 61 at their upper portion are provided with sleeves or enlargements 62, the lower ends of which may rest upon the walls of the openings in the filling end receiver through which the arms 61 project. From the construction described, it will be apparent that by lifting upon the end of the arms 61, the strainer or wire gauze may be raised in the filling end 130

receiver, the filling ends removed, and then the strainer be allowed to drop into normal position.

- The desired mechanism constituting one practical form of the invention will make clear to those skilled in the art that an important feature of the present invention resides in a device or conduit having an inlet or entrance for a filling end, and means for inducing currents of air transversely or across the filling and into the said device or conduit, so that when an end of the filling becomes free it will at once pass along with the currents of air into the conduit and be held in this position until the filling is parted at another point, whereupon the piece of filling will be carried bodily by the air currents away from the weaving instrumentalities.
- Another important feature of the invention is the filling end receiver which serves to gather or receive the pieces of filling as they are carried away from the weaving instrumentalities by the air currents passing into the conduit so that all danger of pieces of filling passing into the shed is avoided. Where the conduit and air currents are employed to remove pieces of filling parted from the shuttle in which the filling has been practically exhausted, the conduit is supported with its entrance between the cloth selvage and shuttle box, and in such position that when the lay is in forward position, the filling extending from the cloth selvage to the adjacent shuttle box will cross the entrance of the conduit so that the currents of air passing into the conduit will pass transversely of the filling. It is obviously within the scope of the present invention to position the filling end conduit to remove the end of filling of the fresh supply following replenishment and after it has been parted at the selvage.

What is claimed is:

1. In a filling replenishing loom, the combination of filling parting means for parting the filling between the cloth selvage and adjacent shuttle-box, a conduit having an entrance between the cloth selvage and adjacent shuttle-box across which the filling to be parted extends, and means for producing currents of air into said entrance to act upon the filling extending across the same and carry said filling into the conduit after it has been parted.

2. In a filling replenishing loom, the combination of two filling parters to part the filling adjacent the cloth selvage and filling carrier respectively, a conduit having an entrance located between said two parters and across which the filling to be parted extends, means for producing currents of air into said entrance to act upon the filling extending across the same and carry the filling into the conduit after it is parted,

and a receiver to receive the filling ends from said conduit.

3. In a filling replenishing loom, the combination of the lay and shuttle-boxes, a filling end conduit, means for supporting said conduit with its entrance between the cloth selvage and a shuttle-box, means for producing currents of air into said entrance to act upon the filling between the cloth selvage and shuttle-box, means for parting the filling adjacent the shuttle to permit the ingoing currents of air to carry the parted end of the filling into the conduit and hold it while the filling is still connected to the cloth selvage, and means for parting the filling adjacent the cloth selvage.

4. In a filling replenishing loom, the combination of a filling parter to part the filling at a point remote from the cloth selvage, a filling parter to part the filling adjacent the cloth selvage, and pneumatic means between said two filling parters to act upon the filling end and remove it after it has been parted.

5. In a filling replenishing loom, the combination of two filling parters to part the filling at points different distances from the cloth selvage, a tube having an entrance portion, means for supporting said tube with said entrance portion normally in operative position between said thread parters, and means for inducing currents of air through said tube to act upon the filling end and remove it after it has been parted.

6. In a filling replenishing loom, the combination of a filling parter to part the filling leading from and at a point adjacent to a shuttle the filling in which has become practically exhausted, a filling parter adjacent the cloth selvage, a filling end conduit, and means for producing currents of air thereinto between the said parters and across the filling to be parted to carry the filling end away after it has been parted.

7. In a filling replenishing loom, the combination of a filling parter adjacent the cloth selvage, a filling parter more remote from said selvage, a filling end conduit having an entrance between said parters, means for yieldingly supporting the conduit with the entrance thereof in position to be crossed by the filling before it is parted from the cloth selvage and shuttle, and means for producing currents of air into said conduit to carry a filling end thereinto.

8. In a filling replenishing loom, the combination of a filling parter adjacent the cloth selvage, a filling parter more remote from said selvage, a filling end conduit having an entrance between said parters, means for yieldingly supporting the conduit with the entrance thereof in position to be crossed by the filling extending from the cloth selvage to the shuttle, means for producing currents of air into said conduit to carry a filling end thereinto.

filling end thereinto, and a filling end receiver to receive the filling end from said conduit.

9. In a filling replenishing loom, the combination of the lay and shuttle-boxes, a filling end conduit, means for supporting said filling end conduit in front of the lay with its entrance between the cloth selvage and adjacent shuttle-box in position to be crossed by the filling end leading from the cloth selvage, means for parting the filling crossing the entrance of the conduit, and means for producing a current of air into the end of said conduit transversely of the filling end crossing the same to cause the filling end to be carried into said conduit.

10. In a filling replenishing loom, the combination of the lay and shuttle-boxes, a filling end conduit, means for supporting the filling end conduit with its entrance between the cloth selvage and adjacent shuttle-box, means for parting the filling from connection with the shuttle, means for producing currents of air into said conduit to carry the parted end of the filling into said conduit when released by the parting means, and a temple thread parter to thereafter part the filling from the cloth selvage to permit the freed piece of filling to be carried through said conduit.

11. In a filling replenishing loom, the combination of the lay and shuttle-boxes, an air conduit supported in front of the lay at the replenishing side of the loom with its entrance between the cloth selvage and adjacent shuttle-box, thread parting means, and means for producing currents of air into the said air conduit to carry the thread into said conduit after the action of the thread parting means.

12. In a filling replenishing loom, the combination of the lay and shuttle-boxes, a filling end conduit, means for supporting the conduit at the filling replenishing side of the loom with its entrance at one side of the cloth selvage in position to be crossed by a filling end leading from the adjacent cloth selvage, and means for producing currents of air into said conduit and transversely of the filling end crossing the entrance thereof, and thread parting means for parting the filling after a call for replenishment that it may be drawn into the said conduit.

13. In a filling replenishing loom, the combination of the lay and shuttle-boxes, an air conduit having an entrance for filling threads, means for supporting the conduit at the replenishing side of the loom with its entrance crossed by the filling extending from the cloth selvage at the replenishing side, means for parting the filling after a call for filling change, means for producing air currents into said entrance of the air con-

duit to draw in the filling after it has been parted, and yielding means permitting said conduit to be moved from normal position.

14. In a filling replenishing loom, the combination of the lay and shuttle-boxes, a filling end conduit, means for supporting the filling end conduit with its entrance above the lay at one side of the cloth selvage in position to be crossed by the filling extending from the cloth selvage, filling thread parting means, means for inducing currents of air into the conduit entrance and transversely of the filling leading from the cloth selvage, a screen communicating with the conduit for intercepting pieces of filling carried through said conduit, and means connected to the screen for removing it and the intercepted pieces of filling.

15. In a filling replenishing loom, the combination of the lay and shuttle-boxes, a conduit, a bearing in which said conduit is movable toward and from the lay, means for yieldingly holding the conduit toward the lay with its entrance in position to be crossed by the filling leading from the cloth selvage and permitting frontward movement thereof, means for parting the filling thread extending from the adjacent cloth selvage, and means for producing currents of air into the conduit entrance to draw in the filling thread after it has been parted.

16. In a filling replenishing loom, the combination of the lay and shuttle-boxes, a conduit, a bearing in which said conduit is movable toward and from the lay, means for yieldingly holding the conduit toward the lay and permitting frontward movement thereof, a receiver connected to and movable with the conduit, means for producing currents of air into the conduit entrance, and means to part the thread extending from the adjacent cloth selvage that it may be drawn into the conduit by the incoming air currents.

17. In a filling replenishing loom, the combination of the lay and shuttle-boxes, filling parting means at the replenishing side of the loom for parting the filling after a call for replenishment, a conduit supported at the replenishing side of the loom and having an entrance across which the filling to be parted extends, and means for producing currents of air into said entrance to act upon the filling extending across the same and draw said filling into the conduit after it has been parted.

In testimony whereof, I have signed my name to this specification, in the presence of two subscribing witnesses.

ALONZO E. RHOADES.
